UNITED STATES PATENT OFFICE.

ARTHUR W. SPRAGUE, OF AUSTIN, ILLINOIS, ASSIGNEE, BY MESNE ASSIGNMENTS, TO THE AMERICAN STEEL AND WIRE COMPANY, OF NEW JERSEY.

LATCH.

SPECIFICATION forming part of Letters Patent No. 634,593, dated October 10, 1899.

Application filed February 6, 1899. Serial No. 704,638. (No model.)

To all whom it may concern:

Be it known that I, ARTHUR W. SPRAGUE, residing at Austin, Cook county, in the State of Illinois, have invented certain new and useful Improvements in Latches or Fastening Devices for Gates and other Uses, of which the following is a description, referring to the drawings as a part of this specification.

The invention relates particularly to self-catching latches or fastenings for gates, doors, and other uses; and its object is to produce a very simple and durable device of this nature which shall be inexpensive to manufacture, yet desirable in appearance and operation. Indeed the device is so simple that it will be readily understood by means of the accompanying drawings, wherein—

Figure 1 is an elevation of fence-post and part of a gate provided with my catch or gate-fastener ready to allow the gate to open or close. Fig. 2 shows the same when fastened, so as to hold the gate. Fig. 3 shows the device reversely placed respectively on the gate and the post. Fig. 4 shows details of part of the device. Fig. 5 shows a modification. Figs. 6 and 7 show modifications of part of the device.

Throughout the drawings like reference-letters indicate like or similar parts.

I have indicated the gates by G and the posts by P. In Figs. 1 and 2 the gate is provided with two projecting studs S, having a relatively small neck and relatively large end. This form serves to prevent any tendency of the latch or fastening device to unfasten by the jarring or slight movement of the parts. The movable member of the catch consists of a vertically-placed rotary body B, having two loops L and supported in position but free to turn by means of two or three brackets or projections F, which in Figs. 1 and 2 are fixed to the post. The rotary or movable member B consists of two wires or small bars twisted together to form the shank, separated to form the loops L, and again twisted together to complete the loops. One of the wires projects at each end, as at E in Fig. 4, to form pins, which project through and turn in the brackets F. When the movable member B is in the position shown in Fig. 1, the gate

may be swung shut, and by striking one side of the loops it will turn them into the position shown in Fig. 2 and so that the loops will surround the projections S and prevent the gate swinging in either direction. 55

I call the open portions L "loops" for convenience, though it must not be understood that I mean thereby to imply that they are formed by looping the wire, for this is not the case, as shown in all the figures of the 60 drawings.

For applying the device to wooden posts I prefer to use spikes having perforated heads to form the brackets, as shown in Figs. 1 and 2; but I may form them of flat iron bars bent 65 to angular shape and secured to the face of the post, as shown in Fig. 5.

In Fig. 3 the device is approximately similar to Figs. 1 and 2, save that the brackets are on the gate and the studs are on the post. 70 Preferably I recess the face of the post opposite the loops L, as shown in Fig. 1, so as to permit the movable member B to lie closer to the post without the post interfering with the rotation of the loop L.

In Fig. 3 I show a modification in which but a single loop L is used.

In Fig. 6 a modification of the rotary member of the fastening device is shown in which the shank B consists of a round iron rod riveted or otherwise secured to the two malleable-iron loops L'. The projecting ends E' are in the form of round pins formed integrally with loops L'. 80

In Fig. 7 a movable member of my device 85 is shown made of strap-iron, with two small malleable or cast iron blocks forming the ends or pins E', the several parts being riveted or otherwise secured together, as shown in the figure.

The use of two or more of the loops and two or more of the studs S fastens the gate at more than one point, and therefore prevents all tendency of twisting the gate either by slamming it or by pushing against it when 95 shut and fastened. I use the term "gate" to include doors and other hinged bodies.

The movable member of the fastening device may be attached to either the gate or the post; but if attached to the stationary post 100

there will be less possibility of its being accidentally turned, so as to unfasten the gate, than when attached to the gate. I depend on the slight friction of the parts to hold the 5 movable member from turning accidentally.

The features that I claim and desire to secure by Letters Patent are the following:

In a latch or fastener for gates and the like, the combination of a rotary member consisting of two or more wires or bars twisted together for portions of their length and sepa-

rated to form one or more loops at one or more points, two or more brackets pivotally supporting the said rotary member and studs coöperating with the said loop or loops, substantially as set forth.

Signed this 6th day of January, 1899, at Chicago, Illinois.

ARTHUR W. SPRAGUE.
